MANUALLY OPERATED KEY DUPLICATING MACHINE

Roy L. Starrett, San Diego, Calif., assignor to
Lloyd S. Starrett, San Diego, Calif.

Application July 15, 1950, Serial No. 174,067

6 Claims. (Cl. 29—76)

1

My invention relates to a manually operated key duplicating machine, and the objects of my invention are:

First, to provide a machine of this class in which the key to be duplicated and the key blank are arranged in superimposed fixed relationship to each other, while the file carriage incorporates a follower and a file in fixed parallel relationship to each other, whereby wear of the moving parts does not affect the fixed relationship of the file relative to the key follower or the spacing of the key and the key blank, which promotes accurate depth control of the file regardless of the amount of wear which takes place in the device;

Second, to provide a manually operated key duplicating machine of this class which is very simple to set up and use;

Third, to provide a manually operated key duplicating machine of this class in which movements of the operator in actuating the cutting file need not be precise, due to the control of the file carriage guided by the master key, which is superimposed in fixed spaced parallel relationship with the key blank being cut;

Fourth, to provide a manually operated key duplicating machine of this class having novel slide bars for controlling the file carriage which are maintained in corresponding reciprocal relationship with each other by a guide bar engaging the slide bar connector which prevents tilting of the file carriage at an angle to the vertical;

Fifth, to provide a manually operated key duplicating machine which is very compact and light in weight in proportion to its utility; and

Sixth, to provide a manually operated key duplicating machine of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a top plan view of my manually operated key duplicating machine; Fig. 2 is a side elevational view thereof; Fig. 3 is a sectional view taken from the line 3—3 of Fig. 2; and Fig. 4 is an enlarged sectional view, taken from the line 4—4 of Fig. 3, showing by dash lines the posi-

2

tion of a key in the upper key holder of my key duplicating machine.

Similar characters of reference refer to similar parts and portions throughout the several views of the drawings.

The frame 1, key holders 2 and 3, key stops 4 and 5, thumb screws 6, 7, 8 and 9, slide bars 10 and 11, file carriage 12, carriage guide clips 13 and 14, slide bar connection 15, guide bar 16, and the file 17, constitute the principal parts and portions of my manually operated key duplicating machine.

The frame 1 is provided with a base 1a, having openings 1b therein, through which bolts or screws may be inserted for supporting the base securely on a bench, table, or other object. Integral with the base 1a is the upright 1c, in which are provided lateral openings 1d and 1e, through which the reduced in diameter end portions 2a and 3a of the key holders 2 and 3 extend. It will be noted that these end portions 2a and 3a are provided with externally screw-threaded nuts, which fix the key holders 2 and 3 securely in certain vertically spaced relationship on the upright portion 1c of the frame 1.

The opening 1e, as hereinbefore described, is vertically extended to permit vertical adjustment of the key holder 3 relative to the key holder 2, so that exact spaced relationship of the key holders 2 and 3 may be accomplished in order to coincide with the spaced relationship of the edge 12a of the guide bar 12b of the file carriage 12, and the lower portion of the file 17. The key holders 2 and 3 are provided with slots 2b and 3b extending through their middle portions, in which the key stops 4 and 5, respectively, are fixed by the thumb screws 6, 7 and 8 and 9, respectively. It will be noted that the thickness of the key stops 4 and 5 is substantially less than the width of the slots 2b and 3b, so that keys may be gripped in the slots 2b and 3b without abutting opposite sides of the key stops 4 and 5, when the width of the slots 2b and 3b is decreased by the thumb screws 6, 7, 8 and 9, which tend to force the key holders 2 and 3 together at opposite sides of the slots 2b and 3b.

The file carriage 12 is a rectangular frame having a master key following guide portion 12a, and is provided with an opposed rail 12c, parallel thereto, and these portions 12a and 12c are interconnected by vertical bars 12d and 12e, as shown in Fig. 2 of the drawings. Secured to the bars 12d and 12e are file supporting fixtures 12f and 12g, in which the file 17 is supported in parallel

relationship to the follower portion 12a, shown best in Fig. 2 of the drawings. The handle 12h is supported on the fixture 12g and provides manual engaging handle for operation of the file carriage 12, in reciprocal relation with the carriage guide clips 13 and 14, which are L-shaped clips secured to the ends of the slide bars 10 and 11, which are reciprocally mounted in bushings 1f and 1g in the frame 1.

Secured to the opposite ends of the slide bars 10 and 11 from the clips 13 and 14 is the slide bar connection 15. This slide bar connection 15 is provided with a central opening 15a slidable over the guide bar 16, which projects from the frame 1 in the opposite direction from the key holders 2 and 3, and surrounding this guide bar 16 is a stop member 16a for limiting the movement of the slide bars 10 and 11 toward the key holders 2 and 3. It will be here noted that the portions 12b and 12c of the file carriage 12 are vertically slidably movable intermediate the ends of the slide bars 10 and 11 and the clips 13 and 14, respectively.

The operation of my manually operated key duplicating machine is substantially as follows:

When it is desired to duplicate a key, the key to be duplicated, designated A in Fig. 3 of the drawings, is placed in the slot 2b of the key holder 2, engaging the upper edge of the key stop 4, and engaging the end thereof at the hilt of said master key A, all as shown best in Fig. 3 of the drawings. The thumb screws 6 and 7 are then tightened, forcing the key holder together at opposite sides of the slot 2b, firmly engaging opposite sides of the master key A in adjacent relation to the follower portion 12a of the file carriage 12.

The blank which is to be made into a duplicate of the key A is supported in the key holder 3, in engagement with the key stop 5 in a similar manner to that hereinbefore described in connection with the master key A. In this position, the blank B is directly below the file 17. The operator of my machine then grasps the handle 12h and reciprocates the file carriage 12 longitudinally of the axis of the file 17, causing the file 17 to cut the blank B until the follower portion 12a of the file carriage 12 engages the master key A.

It will be noted that vertical movement of the file carriage 12 is permitted by the L-shaped clips 13 and 14 at the ends of the slide bars 10 and 11. The spaced relation of the clip portions of the L-shaped clips 13 and 14 are precisely spaced from the ends of the slide bars 10 and 11 to exactly accommodate the thickness of the frame portions 12b and 12c, providing accurate tolerance maintenance in the lateral direction of the file carriage 12, which is actually longitudinally of the master key A.

As the reciprocation of the file carriage 12 progresses, the slide bars 10 and 11 are moved outwardly in the frame 1, through the bushings 1f and 1g, toward the outer end of the guide bar 16, which causes cutting of the blank B by the file 17 only in the exact contour relationship of the tumbler-engaging portions of the key A. The cutting on the blank B is limited by the follower 12a of the file carriage 12 and thus the blank B becomes a duplicate of the master key A when finished. The guide bar 16 provides angular stability of the slide bars 10 and 11 in their reciprocal relation laterally of the frame 1.

When the blank B is finished and becomes a duplicate of the master key A, the thumb screws 6, 7, 8 and 9 are released, permitting both keys

A and B to be removed from the key holders 2 and 3, respectively.

It will be noted that the frame 1 is provided with an elongated slot 1e through which the reduced diameter portion 3a of the key holder 3 is positioned to provide for initial adjustment of the key holder 3 relative to the key holder 2, coinciding with the spaced relation of the lower edge of the follower 12a and the lower surface of the file 17.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a manually operated key duplicating machine, a frame, a pair of slide bars vertically superposed relative to each other in spaced relation, and laterally reciprocally mounted in said frame, guide means, L-shaped in cross-section, on aligned ends of said slide bars, a file carriage horizontally reciprocally mounted on said guide means at right angles to said slide bars and vertically movable relative to said guide means, a pair of horizontal key holders vertically spaced one above the other and fixed to said frame, a file in said file carriage, a follower bar connected to said file in parallel relation therewith and vertically spaced relative to said file, and means for indexing keys and key blanks on said key holders.

2. In a manually operated key duplicating machine, a frame, a pair of slide bars vertically superimposed relative to each other in spaced relation, and laterally reciprocally mounted in said frame, guide means, L-shaped in cross-section, on aligned ends of said slide bars, a file carriage horizontally reciprocally mounted on said guide means at right angles to said slide bars and vertically movable relative to said guide means, a pair of horizontal key holders vertically spaced one above the other and fixed to said frame, a file in said file carriage, a follower bar connected to said file in parallel relation therewith and vertically spaced relative to said file, and means for indexing keys and key blanks on said key holders, said key holders having slotted portions therein, said means for indexing keys therein consisting of plates of a thickness substantially less than the thickness of the key blank, whereby keys may be gripped in said key holders by forcing the side walls of said slotted portions together.

3. In a manually operated key duplicating machine, a frame, a pair of slide bars vertically superimposed relative to each other in spaced relation, and laterally reciprocally mounted in said frame, guide means, L-shaped in cross-section, on aligned ends of said slide bars, a file carriage horizontally reciprocally mounted on said guide means at right angles to said slide bars and vertically movable relative to said guide means, a pair of horizontal key holders vertically spaced one above the other and fixed to said frame, a file in said file carriage, a follower bar connected to said file in parallel relation therewith and vertically spaced relative to said file, and means for indexing keys and key blanks on said key holders, said key holders having slotted portions therein, said means for indexing keys therein consisting of plates of a thickness substantially less

than the thickness of the key blank, whereby keys may be gripped in said key holders by forcing the side walls of said slotted portions together, and screws for forcing the side walls of said slotted portions together and gripping keys on opposite sides thereof.

4. In a manually operated key duplicating machine, a frame, a pair of slide bars vertically superimposed relative to each other in spaced relation, and laterally reciprocally mounted in said frame, guide means, L-shaped in cross-section, on aligned ends of said slide bars, a file carriage horizontally reciprocally mounted on said guide means at right angles to said slide bars and vertically movable relative to said guide means, a pair of horizontal key holders vertically spaced one above the other and fixed to said frame, a file in said file carriage, a follower bar connected to said file in parallel relation therewith and vertically spaced relative to said file, and means for indexing keys and key blanks on said key holders, said key holders having slotted portions therein, said means for indexing keys therein consisting of plates of a thickness substantially less than the thickness of the key blank, whereby keys may be gripped in said key holders by forcing the side walls of said slotted portions together, screws for forcing the side walls of said slotted portions together and gripping keys on opposite sides thereof, said slide bars at the opposite ends thereof from said file carriage having interconnecting means, and a guide bar in connection with said frame, engageable with said interconnecting means for stabilizing said slide bars.

5. In a manually operated key duplicating machine, a frame, a pair of slide bars vertically superimposed relative to each other in spaced

relation, and laterally reciprocally mounted in said frame, guide means, L-shaped in cross-section, on aligned ends of said slide bars, a file carriage horizontally reciprocally mounted on said guide means at right angles to said slide bars and vertically movable relative to said guide means, a pair of horizontal key holders vertically spaced one above the other and fixed to said frame, a file in said file carriage, a follower bar connected to said file in parallel relation therewith and vertically spaced relative to said file, and means for indexing keys and key blanks on said key holders, one of said key holders being vertically adjustably mounted in connection with said frame in order to properly index the master key and a blank relative to the lower surfaces of said file and said follower of said file carriage.

6. In a key duplicating machine, a frame, slide bars horizontally reciprocally mounted in said frame and parallel and vertically spaced relative to each other, a file carriage horizontally reciprocally mounted in connection with said slide bars and vertically movable relative thereto, and a pair of horizontal key holders vertically spaced relative to each other in connection with said frame, parallel with said slide bars, whereby wear of said slide bars is in the same plane with said key holders.

ROY L. STARRETT.
